(57) **CLAIM**

The ornamental design for a bow rake, as shown and described.

DESCRIPTION

FIG. 1 is a three-dimensional view of the top, front and left side of the bow rake;

FIG. 2 is a three-dimensional view of the bottom, back and right side of the bow rake;

FIG. 3 is a front view thereof;

FIG. 4 is a back view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate the portions of the bow rake, which form no part of the claimed design.

1 Claim, 8 Drawing Sheets
